RAILWAY JOURNAL LUBRICATOR STRUCTURE
 James J. Hennessy, % Hennessy Lubricator Co. Inc.,
 605 Guilford Ave., Chambersburg, Pa.
 Filed Dec. 11, 1961, Ser. No. 158,284
 7 Claims. (Cl. 308—243)

The invention relates to lubricant distributors for railway axle boxes and comprises a pad and pad support parts adapted to rest upon the bottom wall of an axle box and to feed lubricant by capillary action from the sump formed by the bottom of the box to the surface of an axle journal upon which the box is carried. The invention is particularly adapted for but not limited for use in an axle box of the type described in my copending application filed November 3, 1961, Serial No. 149,922, which embodies an axle box having a horizontal bottom wall.

The general object of the invention is to facilitate the reception, feeding and distribution of oil by the pad structure. This object is accomplished by elevating the bottom of the pad above the bottom of the sump and providing for the supply of oil to an intermediate portion of the pad at points spaced above the bottom of the pad.

Another object is to facilitate the insertion and removal of the pad into and out of the open end of the axle box. This provides for the ready inspection, cleaning and replacement of the pad, or parts thereof.

These objects are attained by the structure shown in the accompanying drawings in which:

FIG. 1 is a top view of the lower portion or cellar of an axle box of the type referred to above, the lower half of the figure showing the platform upon which the pad is mounted, and the upper half of the figure showing the pad positioned thereon.

FIG. 2 is a longitudinal vertical section on line 2—2a of FIG. 1. The left hand portion of the figure is also identified as being on line 2—2 of FIG. 3, and the right hand portion of the figure as being on line 2a—2a of FIG. 3.

FIG. 3 is a transverse vertical section on line 3—3 of FIG. 1.

The axle box comprises a cast metal upper half 1 and a sheet metal lower half 2 detachably secured thereto and these parts are described in more detail in the above-mentioned application. The box is supported by a bearing 3 carried on journal 4 and the box supports the axle load through ribs 5 in the usual manner.

Mounted on the box bottom wall 7 is a platform, or two platform sections 9 comprising sheet metal or plastic members with downturned and out-turned flanges 10 at their ends for supporting the member body spaced above the box bottom wall. An upstanding center partition 12 is positioned lengthwise of the center of the platform 9 and is similarly flanged at 13 for support upon the box bottom wall although the partition could be supported upon platform 9. The partition extends about half the distance between the box bottom wall and the lower face of journal 4. Platform 9 and partition 12 are apertured as indicated at A substantially throughout their respective lengths and widths.

At each side of partition 12 is a pad structure comprising a fabric sheet 15, such as canvas, doubled and folded as shown to form a series of pockets 17, 18, 19. The fabric sheet 15 forming the sides and tops of these pockets incorporates tufted yarn exteriors 20 which form capillary feeding elements leading the oil from the sump to the journal. Filler slabs 21, 22 of springy material such as foam rubber or similar synthetic material are inserted in pockets 18 and 19 and hold the pockets dis-

2

tended. Outer pocket 19 and slab 22 are deeper than pocket 18 and slab 21.

There is no slab in the innermost pocket 17 which is filled by the downwardly extended and folded tufted yarn 5 coated fabric. The tufted yarn coating similarly extends down the exterior wall of the pad and terminates at 25. Spaced tapes 27 are secured to the lower margins of fabric 15 and yarn 20 and extend across the bottom portions of the pockets.

10 The structure described above permits oil to flow directly and freely to the tufted yarn feeding elements for the full width of the sump and for approximately half the distance between the bottom of the box and the journal surface. This results in supplying oil quickly and more 15 freely than is obtained with pads as previously used which are pressed against the bottom of the box and only provide a supply of oil to the innermost parts of the pads by its soaking through the pad material, the transmission qualities of which are affected by the compression of the material fibers together, by dirt and sediment which may coat the lower portions of the pad.

20 Preferably the outermost upright layers or feeding elements are engaged by side members 28 of sheet metal or plastic positioned as shown with their margins resting 25 against the sides and bottom of box 2. Or these outer layers may bear against inwardly offset portions 29 of the box cellar side walls. This holds the layers upright and avoids separation of the doubled layers.

25 30 The hollow center partition 9 and the unobstructed passage thereto from all parts of the sump permit oil to flow freely to the innermost feeding elements of the pad at a level only about 1" from the journal surface and from which it is fed directly by capillary action to the lowermost part of the journal where the application of oil is most effective. The feeding elements have about seven times as much surface exposed directly to oil as in the ordinary pad, assuring more rapid absorption and supply to the journal. This shortened distance of capillary feeding and the increased absorption area is particularly advantageous during cold weather.

35 40 With the platform and upright members secured directly to the box, for example by welding as indicated, the positioning of the pads will be assured, and it is unlikely that wider unshaped single pads will be substituted for the more effective pad shown.

45 50 The inner end of the axle box includes an annular pocket 31 of channel cross section adapted to receive a seal or guard for dust and oil to prevent the loss of oil from the box. This seal is shown in the above-mentioned application and is disclosed in another application filed February 15, 1961, Serial No. 89,559. The seal and baffle 30 permit a car equipped with axles having improved lubricators to be operated at high speeds and dumped without undue loss of oil.

55 60 Variations in the details of the structure may be made without departing from the spirit of the invention and the exclusive use of modifications of the disclosure within the terms of the claims is contemplated.

65 66 What is claimed is:

1. In a railway axle box lubricator, a platform with depending supports disposed to engage the bottom wall of an axle box and hold the platform spaced upwardly from said wall, an upstanding substantially rigid hollow longitudinal member disposed lengthwise of the middle portion of the platform, individually removable pads at opposite sides of said upstanding member and including narrow upright pockets of sheet fabric, the sides and top faces of said pads including tufted yarn exteriors and forming capillary feeding elements, elastic fillers holding the pockets distended, said platform and central member having openings substantially throughout their areas for

admission of lubricant directly to the feeding elements, and the upper faces of the feeding elements being concaved downwardly to adapt the same for fitting about the lower face of an axle journal to which the lubricator is applied.

2. A railway axle box lubricator according to claim 1 in which the platform and upstanding central member are formed separately of substantially rigid sheet material and have flanged lower portions for individual support on a journal box bottom wall and are apertured substantially throughout their length and width and are disposed in face to face contact with the adjacent portions of the pad feeding elements.

3. A railway axle box lubricator according to claim 1 which includes substantially rigid upstanding side members adjacent the sides of the platform confining the pads and holding them upright.

4. A railway axle box lubricator according to claim 3 in which each pad has a plurality of pockets between the central member and the side of the platform and the pockets have parallel sides and are of increasing height toward the platform sides whereby the top face of the pad is downwardly concave, to adapt it to fit an axle journal, while the sides of the pockets remain straight and in contact with each other and with the central member and side member.

5. In a railway axle box lubricator, a horizontal platform with relatively short depending marginal support portions, an upstanding substantially rigid hollow central member disposed lengthwise of the middle portion of the platform, upstanding substantially rigid side members spaced transversely of the platform from said central member, individually removable pads at opposite sides of said central member and confined and held upright by the

same and said side members, each pad including a plurality of pockets having tufted yarn exterior faces, individual elastic fillers in said pockets holding the upper and lower portions of the pockets in spaced relation, said platform and members having openings near the bottom of the pad for admission of lubricant to tufted yarn portions of all of the pads, the pockets and fillers being of progressively increasing height from the central member toward the side members and affording a generally downwardly arcuate top face adapted to fit against the lower portion of an axle journal to which the lubricator is applied while the lower ends of the pockets are supported on the horizontal platform.

6. In combination with a railway axle box cellar forming a sump for lubricating oil, a platform across the sump and supported at a level spaced above the bottom of the sump and perforated substantially throughout its length and width, a lubricant distributing pad comprising upright parallel layers of tufted yarn fabric, forming capillary feeding elements, and intermediate slabs of upright self-supporting springy material holding said layers upright, and spaced apart tape-like strips across the bottom of said layers and slabs and secured to the lowermost portions of said layers and leaving the lower edges of the upstanding layers exposed, through said platform apertures, to oil in the sump.

7. The combination set forth in claim 6 which includes an upstanding narrow hollow partition intermediate the sides of the sump and between spaced upright feeding elements and open at the bottom throughout its length and height.
